UNITED STATES PATENT OFFICE.

FRANK C. MARQUARDT, OF BROOKLYN, NEW YORK, ASSIGNOR TO AMERICAN BANK NOTE COMPANY, OF NEW YORK, N. Y., A CORPORATION OF NEW YORK.

FEEDER FOR ROTARY PRINTING MACHINES.

Application filed February 9, 1922. Serial No. 535,157.

My invention relates to feeders for rotary printing machines, and more particularly to a mechanism of this character for use in an undersurface printing machine.

5 In undersurface rotary printing machines, dampened sheets of paper are used, said sheets being fed directly between the plate and the blanket upon the impression cylinder or D-roll. The feed of the paper 10 during the printing interval is a friction feed between said plate and said cylinder, the sheets being collected directly from the plate.

Heretofore such machines have had incorporated therein a reciprocatory feed shelf actuated in synchronism with the printing couple, the operator placing the sheets one at a time upon said shelf in the proper relation to side and back gauges or 20 gauge markings to secure the proper register of the sheet with the design upon the plate, which is essential particularly in multicolor work where two or more impressions are necessary in the completed job.

25 The forward edge of the sheet in the type of feed shelf above referred to, projected slightly beyond the forward edge of the shelf, great care being required on the part of the operator to prevent skewing of the sheet when the forwardly projecting edges 30 above referred to are first engaged between the co-acting surfaces of the members of the printing couple.

35 While the slow speed of undersurface rotary presses as compared with rotary presses of other types, will permit ample time for properly positioning each sheet upon the feed shelf as required, there is always likelihood, with mechanical feeders, 40 of the sheet being disturbed after having once been properly positioned upon the shelf, notwithstanding the exercise of the greatest care in the location of the sheet in relation to the side and rear gauges or 45 gauge markings.

With the above conditions in mind, I have produced a feeder for rotary presses of the undersurface type wherein the operator will feed the sheet against rectilineally disposed 50 front gauge stops with relation to a proper side gauge or mark, which front gauge stops will have no function in feeding the sheet to the printing couple but will serve merely to ensure the proper longitudinal

register of the sheet preparatory to a subsequent feeding movement of the sheet under the control of a mechanism which will hold the sheet in its entirety against displacement upon the feed shelf.

In order to bring the front gauge mechanism into close juxtaposition to the line of engagement between the members of the printing couple and thus permit the feeding movement of the sheet to be accomplished by a short reciprocatory movement 65 of the feed shelf, and at the same time increase the interval during which the sheet may be fed in relation to said gauges, I provide a suitable fixed support co-operating with said gauges, which will have the 70 two-fold effect of affording a rigid support for the front edge of the sheet, projecting beyond the forward edge of the reciprocatory feed shelf, and permit the feeding of a sheet of paper with relation to said 75 front gauge without regard to the return reciprocatory movement of the feed shelf. By this construction the operator may advance a dampened sheet in close proximity to the sheet being drawn between the 80 members of the printing couple, and thus have it in position to immediately engage the front gauge preparatory to the succeeding feeding movement of the reciprocatory shelf immediately upon the restoration 85 of the front gauge to its normal position, a condition which gives the operator a little greater time within which to properly adjust the sheet with relation to the front and side gauges. The actuation of the front 90 gauge to position it is so as to stop the sheet and true up the front edge thereof, and to pass from its engagement with the sheet to permit the subsequent feeding movement thereof with relation to the feeding 95 couple, is entirely automatic and synchronized with the movement of the form or plate cylinder, to ensure accuracy in the timing of the movement of said front gauge with relation to the printing interval and 100 with the actuation of the reciprocatory feed shelf. The employment of the fixed support adjacent the front gauge will not only bring the forward edge of the dampened sheet in close proximity to the line of engagement of the members of the printing couple, but will ensure a definite uniform 105 movement of each sheet by the operator in

positioning it with relation to the gauge stops, and at the same time cause a very short movement of the sheet under the control of the reciprocatory feed shelf to bring 5 the forward edge of the sheet into a position where it can be engaged between the members of the printing couple. In this manner the edge of the sheet will not be permitted to drop toward the printing plate 10 by reason of the lack of elasticity inherent to the paper.

The construction of a feeding mechanism made in accordance with my invention is such that a proper clear field is afforded for 15 the advancement of the sheet by the operator into engagement with the front gauge stops, a positive feeding movement is imparted thereto by means of grippers carried by the reciprocatory feed shelf, and the 20 action of the grippers is relieved while the sheet receives movement under the control of the members of the printing couple. The above conditions require great nicety in the timing of the relative movement of the 25 front gauge stops, the feed grippers and the reciprocatory feed table with regard to each other and with the plate upon the form or plate cylinder, the various actuating mechanisms being so set or being capable of such 30 adjustment as to secure accuracy in such timing. Not only is it necessary to ensure proper engagement of the feed grippers with the sheet for the feeding movement of the reciprocatory feed shelf, but to disengage 35 these grippers substantially simultaneously with the passage of the forward edge of the sheet between the members of the printing couple in order to avoid any necessity for uniformity in the speed of said shelf and of the peripheral speed of the 40 printing couple.

With the movement of front gauges any 45 necessity for readjustment of the feed mechanism or the gauge stops for sheets of different lengths is made unnecessary although it is preferable, as will more fully appear hereinafter, to provide for a lateral adjustment of the stops, to adapt the mechanism to sheets of different widths.

50 In a machine made in accordance with my invention, a sheet is permitted to project well in advance of the edge of the movable feed shelf presented towards the printing couple and is supported throughout substantially its entire length and breadth, the support at its forward edge being sufficiently close to the engagement line of the printing couple to prevent such a folding or buckling of the sheet as would interfere with the sheet being fed perfectly flat upon the plate.

55 The invention consists primarily in a feeder for rotary printing machines embodying therein a fixed support adjacent the printing line of the printing

couple adapted to receive a portion of the sheet to be fed, adjacent its forward edge, a front gauge stop movable towards and from said support, actuating means for said stop whereby it 70 will be alternately interposed in the path of the sheet so as to engage its forward edge and position it with relation to the printing couple for longitudinal register, and moved away from said support to permit the sheet 75 to be fed, and means adapted to impart feeding movement to a sheet across said support; and in such other novel features of construction and combination of parts as are hereinafter set forth and described, and 80 more particularly pointed out in the claims hereto appended.

Referring to the drawings:—

Fig. 1 is a side view of the printing couple 85 of a rotary printing press and a feeder made in accordance with my invention associated therewith;

Fig. 2 is an enlarged view of the feeding mechanism with the parts in the position immediately preceding the initial feeding 90 movement of the sheet;

Fig. 3 is a detail view of the portions of the printing mechanism adjacent the printing couple, showing the relation of parts 95 following the completion of the feeding of the sheet by the feeder mechanism;

Fig. 4 is a plan view of Fig. 1; and

Fig. 5 is a detail view of the front stop gauges.

Like numerals refer to like parts throughout the several views.

In the embodiment of my invention shown in the drawings, I employ an ordinary printing couple consisting of a plate cylinder 10 adapted to carry two undersurface printing plates and the usual impression cylinder or D-roll 11 associated therewith. Said impression cylinder or D-roll is provided with co-acting gears 12 and 13 and their associated starting and stopping mechanisms, all of which are of the usual and well known construction, and therefore shown merely conventionally in the drawings.

110 The inking, wiping and polishing mechanisms incidental to a press of this type are not shown, as they constitute no part of the combination of the invention. The delivery mechanism is omitted from the drawings for like reason.

115 Mounted in the space between the peripheries of the cylinder 10 and the impression cylinder or D-roll 11 is a support 14 extending for substantially the entire width of said D-roll, this support having a smooth upper surface and extending as close to the meeting line of the members of the printing couple as is feasible, in view of the necessity 120 for the provision of clearance for the movement of a front gauge stop associated there-

with. This support 14 is adapted to receive and sustain the portion of the dampened sheet of paper to be fed, adjacent the forward edge thereof in the direction of its feeding movement, and is fixed so far as the feeding movement of a sheet is concerned. The sheet, which is indicated at 15 in the drawings, is positioned upon said support preparatory to each printing cycle of the 10 impression cylinder or D-roll, by hand, and passes thereover under the control of means imparting movement to the sheet during the initial feeding movement, and as a result of the engagement of the sheet between the 15 plate upon the cylinder 10 and the blanket upon the impression cylinder or D-roll 11 during a later stage of such feeding movement.

Co-operating with the support 14 are a 20 plurality of rectilineally positioned front gauge stops 16 which are adapted to be so actuated as to be moved towards said support and be interposed in the path of the sheet so as to engage the forward edge thereof as it is fed by hand, and thus prevent this edge from passing beyond said support, and cause the sheet to be accurately positioned for longitudinal register of the 25 impression upon the sheet; and to be moved 30 away from said support to permit the sheet to pass thereover during the mechanical feeding of the sheet. Said front gauge stops are carried by an oscillatory shaft 17 acted upon by a spring 18 adapted normally to raise said stops out of the operative 35 relation to said support 14, so as to afford clearance for the feeding of the sheet. Carried by said shaft is a crank arm 19 having an anti-friction roller 20 thereon arranged in the path of movement of a cam 21 carried by and rotatable with the gear 12 of the impression cylinder so as to move the stops toward the support 14, said cam being so positioned and formed as to synchronize the functioning of said gauge 40 stops with that of the printing couple. When the cylinder 10 is adapted to carry two plates, there will be two such cams 21, since with this condition the impression cylinder or D-roll 11 will rotate twice with each 45 rotation of the cylinder 10, and it will be essential that the stops 16 have one complete cycle of operation with each revolution of said impression cylinder or D-roll.

The cam 21 is adjustably mounted upon the gear 12 by means of a segment 22, fixed in relation to said gear, said cam being carried by a slide 23 having slots 24 therein through which the bolts 25 pass, said bolts also serving to secure the segment 22 in relation to said gear. The slide 23 carries a plurality of oppositely disposed abutments 26 and 27 acting between which is a screw 28 carried by a spoke of the gear 12, thus permitting minute circumferential ad-

justment of said cam, so as to accurately time the raising of the stops 16 with relation to the initial advancement of the sheet 15 towards the printing couple.

In the form of the invention shown, the 70 front gauge stops 16 are formed of a sheet of metal having converging arms provided with downturned forked ends 29, which forked ends as shown, straddle lugs 30 projecting from the forward edge of the support 14 and are interposed in the path of movement of the sheet. The stops 16 are carried by a head 31 pivotally mounted in a split collar 32 carried by the shaft 17, an adjusting screw 33 mounted in said collar 80 permitting the positioning of the head 31 to bring the forked ends 29 in the proper relation to the lugs 30, and the set screw 34 being employed to lock them in this position.

The construction described is merely for the purpose of securing a proper adjustment of the front gauge stops with relation to the support 14. The split collar 32 is used to permit adjustment of said stops laterally of said machine, the support 14 being carried by a laterally movable slide 35 so as to permit its adjustment laterally of the machine. The lateral adjustment above referred to is to accommodate the front gauge 95 stops to sheets of different widths and to cause the stops 16 to engage said sheets at points equidistant from the longitudinal center line of the sheets, irrespective of its width.

The main frame of the machine has a reciprocating feed shelf 36 mounted thereon in any desired manner, as by means of the anti-friction rollers 37 and suitable guides or ways 38, actuating means for said shelf 105 being provided so as to give it a timely movement towards the printing couple to advance the sheet into engagement therewith and restore it to its normal position while an impression is being made.

A fixed shelf 39 is provided adjacent said movable feed shelf so as to support a pile or stack of dampened sheets convenient to the hand of the operator.

Carried by and movable with the shelf 115 36 are brackets having mounted therein a rock shaft 40 positioned above said shelf sufficiently to permit sheets to be fed thereunder. The shaft 40 carries a plurality of gripper fingers 41 adapted to engage a sheet 120 upon the shelf 36 and prevent movement of such sheet upon said shelf while the sheet is being advanced towards the printing couple as a result of the forward reciprocating movement of said shelf.

Each of the gripper fingers 41 is provided with a flat spring portion 42 adapted to engage the sheet and flex under such engagement so as to develop a light pressure upon the shelf through the sheet, with 130

the two-fold object of developing the desired pressure upon the sheet to avoid displacement thereof with relation to the shelf, and avoid any nicety in the adjustment of 5 the gripper fingers to compensate for unevenness in the surface of the shelf. The gripper fingers 41 are mounted upon the shaft 40 by means of collars 43 having a sliding fit on said shaft, and secured against 10 rotary movement thereon by means of a set screw 44.

The shaft 40 is acted upon by suitable means having a normal tendency to rotate it in a manner to engage the gripper fingers 15 with the feed shelf, as the torsion spring 45, means being provided to control the functioning of said spring in engaging said gripper fingers with, and in disengaging them from, the sheet, as may be required in 20 feeding a sheet to the printing couple.

As will more fully appear hereinafter, the controlling means above referred to must embody therein means whereby the spring 25 45 will be held in tension with the gripper fingers 41 disengaged from the feed shelf while a sheet is being withdrawn from said shelf by the printing couple and until a succeeding sheet has been positioned with relation to the front gauge stops, and will 30 be released to cause the fingers to engage the sheet just prior to, and during, the feeding of the sheet under the control of said shelf. Furthermore, upon the completion of such feeding movement of the sheet, said fingers 35 must be instantly disengaged from the sheet so as to avoid any drag upon the sheet while it is being fed by the printing couple, and permit the means holding the grippers away from the shelf, to act.

40 Hence this controlling means will consist of three mechanisms, the functionings of which are synchronized with each other, with the actuation of the front gauge stops, with movements of the feed shelf and with 45 the operation of the printing couple.

The means for preventing the engagement 50 of the gripper fingers 41 with the shelf 36 while a sheet is being positioned in relation to the front gauge stops 16, consists of a stop arm 46 carried by the shaft 40 and a latch dog 47 carried by one of the brackets co-operating therewith, and adapted to be automatically set to prevent rotation of the shaft 40 by means of a torsion spring 48 acting 55 thereon. The dog 47 is a mere holding dog and is not designed nor adapted to impart movement to the shaft 40.

The holding dog 47 is adapted to be disengaged from the stop arm 46 by means of 60 a push rod 49 mounted in a suitable bearing 50 on the frame of the machine. One end of this rod is positioned adjacent the dog 47 when the feed shelf is at the limit of its return movement, and the other end thereof is 65 pivotally connected with a rock arm 51.

Mounted adjacent the arm 51 is a cam 52 having a short rise engaging an anti-friction roller 53 mounted upon said arm, said cam receiving two full revolutions with each revolution of the cylinder 10 through any 70 desired power transmission mechanism, as the chain and sprocket mechanism 54 receiving its power from the gear wheel 12. The cam 52 is so set as to operate the rod 49 to disengage the dog 47 from the arm 46 75 just prior to the initial movement of the shelf 36 towards the printing couple when feeding a sheet.

A spring 55 acts upon the arm 51 to retract the rod 49, the stop 56 limiting the 80 movement of said arm by said spring.

One side frame of the machine has mounted thereon a fixed wedge 57 positioned adjacent the printing couple and adapted to be engaged by a roller 58 upon an arm 59 carried by the shaft 40 and oscillate said shaft with the primary object of lifting the gripper fingers 41 to disengage them from the sheet being fed, and raise the arm 46 so as to permit the dog 47 to pass below and engage same so as to hold the gripper fingers elevated until the succeeding actuation of the rod 49. The arm 59 is of a length to engage the wedge 57 towards the end of the 90 forward feeding movement of the shelf 36. 95

The actuating means for the feed shelf 36 comprises a cam 60 carried by and rotatable with the shaft of the gear wheel 12. This cam has two rises and falls 61—62, and is so set as to time the actuation of the feed shelf with due regard to the initial engagement of each plate upon the cylinder 10 with the impression cylinder or D-roll 11. 100

105 Mounted upon the frame of the machine adjacent the printing couple is a swing arm 63 carrying an anti-friction roller 64 engaging the cam 60. Pivotally connected with the arm 63 is a connecting rod 65, which is also connected with a short crank 66 upon a rock shaft 67 having a long crank 68 secured thereto. Extending from the crank 68 and connected with the table 36, is a pitman 69 by means of which a forward movement is imparted to said table. The return movement is effected by means of a weight or weights 70 connected with said table by a flexible connection or connections 71 passing over suitable guide pulleys. 115

120 The operation of the herein described feeder for rotary printing machines is substantially as follows:—

In an undersurface printing press, the sheets are damped and stored in a stack adjacent the reciprocating feed shelf 36 so as to be convenient to the hand of the operator. When a feeding mechanism made in accordance with my invention is used in a press of this type, the sheets are removed from the stack one at a time by the operator, placed upon the shelf 36 and advanced 125 130

thereon by hand until the portion of the sheet adjacent the forward edge thereof rests upon the support 14 with the forward edge engaging the downturned ends 29 of

5 the front gauge stops 16, which will cause the sheet to be accurately positioned with relation to the design upon the printing plate when the sheet is subsequently fed to the printing couple. The position of said 10 stops with each printing operation will be the same, thus causing all sheets fed to the press to be similarly positioned with relation to the plate longitudinally thereof.

15 The lateral positioning is secured by means of gauge marks upon the feed shelf, or if desired any other side guage may be used instead of such marks.

20 In feeding the sheet with relation to the support 14 and stops 16, it is passed beneath the gripper fingers 41-42.

25 When the position of parts is such as is shown in Fig. 1 of the drawings, a sheet has been fed and the plate cylinder is in a position where the stops 16 have been moved in an upward forward arc from the edge of the sheet 15, thus providing a clear field for the advance of the sheet 15 toward the meeting point of the plate upon the plate cylinder 10, and the blanket upon the impression cylinder or D-roll 11. At this 30 stage the gripper fingers 41-42 are still held out of engagement with the sheet upon the shelf 36 by the engagement of the latch dog 47 with the arm 46, the rise 61 of the cam 60 being disengaged from the roller 64 upon the swing arm 63, and the cam 52 being engaged with the roller 53 upon the arm 51.

35 With the continued movement of the cylinder 10, the cam 52 will move the arm 51 and with it the rod 49, which will engage and trip the dog 47, permitting the spring 45 to rock the shaft 40 so as to engage the resilient ends 42 of the gripper fingers 41-42 with the sheet 15 upon the shelf 36 and thus positioning these parts preparatory to the feeding movement which will immediately follow as a result of the engagement 50 of the rise 61 upon the cam 60 with the roller 64 and the resultant movement of the shelf 36 through the link 65, crank 68 and pitman 69. Just prior to, and during the feeding movement of the shelf 36, the various parts will be in the position as shown 55 in full lines in Fig. 2, except the shelf itself and the actuating means therefor.

60 With the movement of the shelf 36, the gripper fingers 41-42 will ensure a positive feeding movement of the sheet 15 in its entirety with the shelf, the forward portion of the sheet sliding freely over the support 14 and coming to rest upon the printing plate substantially simultaneously with 65 the engagement of the blanket upon the impression cylinder or D-roll 11 therewith.

As the sheet reaches this position, the roller 58 will engage the wedge 57 and raise the arm 59 so as to disengage the fingers 41-42 from the sheet, thus permitting the sheet to be drawn from the shelf 36 by the printing couple. During the feeding movement of the sheet under the printing couple, the spring 18 will maintain the front gauge stops 16 in their position above the support 14.

75 During the advance movement of the shelf 36, the edge thereof adjacent the support 14 will pass over said support, this edge being reduced in thickness, as compared with the rest of the shelf, for this purpose.

80 The relation of parts substantially simultaneously with the engagement of the sheet 15 between the members of the printing couple, is shown in Fig. 3 of the drawings.

85 Substantially simultaneously with, or immediately following, the passage of the sheet 15 from the shelf 36 under the control of the printing couple, the cam 21 will engage the roller 20, rotate the shaft 17 against the tension of the spring 18 and thus move 90 the front gauge stop 16 downwardly so as to interpose them in the path of movement of the succeeding sheet, which the operator will be advancing upon the shelf 36 in close proximity to the sheet being fed by the 95 printing couple.

100 As the fingers 41-42 are raised by the engagement of the roller 58 with the wedge 57, the spring 48 will rotate the latch dog 47 bringing it under the arm 46 so that as the shelf 36 recedes, the gripper fingers 41-42 will be held in the elevated position to afford clearance for the feeding of the 105 succeeding sheet with relation to the support 14.

110 The length of the rise and fall 61 or 62 upon the cam 60 may be such as to hold the shelf 36 stationary during any part of the feeding movement of the sheet 15 by the printing couple, although it is preferable to use a short length of cam riser so that the feeding of succeeding sheets may be accomplished while this shelf is stationary and in the fully retracted position.

115 By using forked ends 29 upon the front gauge stops co-operating with the tongues 30, the ends of said arms overlap the forward edge of the support 14, the accurate adjustment of said arms by the screw 33 120 eliminating any necessity for any high degree of precision in the formation of the cam 21. The circumferential adjustment of the cam 21 with relation to the gear 12 is largely for purposes of timing the actuation of the front gauge stops with relation to the movement of the feed shelf, since the length of plate is not a factor to be considered, adjustment to accommodate the printing couple to different lengths of plates 125 being effected through the actuation of the 130

form or plate cylinder, and there being as a rule little variance in the lengths of different plates.

Movement of the front gauge stops 16 when positioning them with relation to the support 14 is against the tension of the spring 18, the function of said spring being to normally elevate said stops when such movement is permitted by the operative 10 relation of the cam 21 and the roller 20.

The trip mechanism for the dog 47 has only a short movement, which occurs prior to any feeding movement of the shelf 36, this mechanism having no movement with 15 the shelf.

The wedge 57 is operative only at or toward the end of the feeding movement of the shelf 36.

If sheets of different widths are used, it 20 is desirable to adjust the front gauge stops laterally of the machine, which is permissible by reason of the construction described, the support 14 being similarly adjusted to preserve the proper relation of the tongues 25 30 and the forked ends 29.

It is to be observed that by reason of the position of the support 14 between the converging surfaces of the plate upon the cylinder 10, and the blanket upon the impression cylinder or D-roll 11, and in fairly close proximity to the meeting point of the two curved surfaces, the feeding of the sheet 15 is accomplished by a short movement of the shelf 36, the gripper finger releasing mechanism being operative, by reason of the fixed position of the wedge 57, substantially simultaneously with the engagement of the sheet between the members of the printing couple, thus avoiding any 40 necessity for any concordance in the lineal speed of the shelf 36 and of peripheries of the members of the printing couple.

The use of the fixed support 14, and the term fixed is used to define the condition 45 of the shelf with relation to the feeding of the sheet as compared with any manner of adjustment, permits the projection of a considerable portion of the sheet adjacent its forward edge beyond the forward edge 50 of the reciprocatory feed shelf 36 while affording a suitable support therefor during the hand feed of the sheet.

The gripper fingers 41-42 hold the sheet 55 with sufficient permanency to avoid any loss of register through displacement of the sheet during its feeding movement under the control of the shelf.

As heretofore stated, the actuating cams for the front gauge stops, and for the feed 60 shelf, will be determined by the number of plates used upon the cylinder 10, the functioning of the gripper release mechanism being automatic as a result of the movement of the shelf 36. The design of the actuating 65 mechanisms for the trip mechanism for

the dog 47, may also be varied according to the number of plates, to bring this mechanism into accord with the actuating means for the feed shelf.

It is not my intention to limit the invention to the precise details of construction shown in the drawings, it being apparent that such may be varied to conform the invention to different designs of undersurface printing presses, the invention being particularly adapted for use with this type of press, wherein dampened sheets of high-grade paper are employed, and accuracy in the feeding thereof is desirable, not only to avoid wastage through improper impressions, but to effect a saving of paper as a result of a reduction in the width of margins which must be subsequently trimmed during the finishing of the sheets.

Having described the invention, what I 85 claim as new and desire to have protected by Letters Patent, is:—

1. A feeder for rotary printing machines embodying therein the combination with a printing couple consisting of a plate cylinder and an impression cylinder, of a fixed support adjacent the printing line of the printing couple adapted to receive a portion of the sheet to be fed, adjacent its forward edge, a front gauge stop movable 90 towards and from said support, actuating means for said stop whereby it will be alternately interposed in the path of the sheet so as to engage its forward edge and position it with relation to the printing couple 100 for longitudinal register, and moved away from said support to permit the sheet to be fed, a reciprocatory member adapted to receive and support a sheet in relation to said support and said front gauge stop positioned adjacent said support and adapted to pass thereover, means carried by said member for holding a sheet in relation thereto, and intermittently operative means operative upon said member, whereby a 110 sheet is simultaneously fed in relation to said support and said front gauge stop and receives feeding movement by said member across said support and said stop to between the members of the printing couple. 115

2. A feeder for rotary printing machines embodying therein the combination with a printing couple consisting of a plate cylinder and an impression cylinder, of a fixed support adjacent the printing line of the 120 printing couple adapted to receive a portion of the sheet to be fed, adjacent its forward edge, a front gauge stop movable towards and from said support, actuating means for said stop whereby it will be alternately interposed in the path of the sheet so as to engage its forward edge and position it with 125 relation to the printing couple for longitudinal register, and moved away from said support to permit the sheet to be fed, a re- 130

- ciprocatory feed shelf, positioned adjacent said support and adapted to pass thereover, grippers carried thereby, means adapted to cause engagement of said grippers with a sheet prior to a feeding movement of said shelf, intermittently operative means acting upon said shelf whereby a sheet may be simultaneously fed in relation to said shelf, said fixed support and said front gauge, and 5 will thereafter be fed across said support, actuating means for said reciprocatory feed shelf, whereby said shelf will be moved toward said printing couple after said stop has been moved away from said support 10 15 to advance the sheet to a position where it will be engaged between the plate upon said plate cylinder and said impression cylinder, and means adapted to disengage said grippers from the sheet substantially simultaneously with the engagement of the forward edge of the sheet by the members of the printing couple.
3. A feeder for rotary printing machines embodying therein a fixed support adjacent the printing line of the printing couple adapted to receive a portion of the sheet to be fed, adjacent its forward edge, a front gauge stop movable towards and from said support, actuating means for said stop whereby it will be alternately interposed in the path of the sheet so as to engage its forward edge and position it with relation to the printing couple for longitudinal register, and moved away from said support 25 to permit the sheet to be fed, a reciprocatory feed shelf, grippers carried thereby, means normally holding said grippers out of engagement with the feed shelf, means operative independently of the movement of the shelf for releasing said grippers prior to the initial feeding movement of the shelf, and means adapted to disengage said grippers from the sheet substantially simultaneously 30 with the engagement of the forward edge of the sheet by the members of the printing couple.
4. A feeder for rotary printing machines embodying therein a fixed support adjacent the printing line of the printing couple adapted to receive a portion of the sheet to be fed, adjacent its forward edge, a front gauge stop movable towards and from said support, actuating means for said stop whereby it will be alternately interposed in the path of the sheet so as to engage its forward edge and position it with relation to the printing couple for longitudinal register, and moved away from said support to permit the sheet to be fed, a reciprocatory feed shelf, a rock shaft carried by said shelf, gripper fingers carried by said shaft, a spring acting thereon and having a normal tendency 45 to rotate said shaft so as to engage the gripper fingers with the feed shelf, a crank arm carried by said shaft, a fixed cam adapted to engage said crank arm toward the limit of the feeding movement of the feed shelf, a stop upon said shaft, a holding dog having a normal tendency to engage said stop, actuating means adapted to impart reciprocatory movement to the feed shelf, and a trip mechanism operative upon said holding dog actuated in synchronism with said last named actuating means, whereby said latch member will be disengaged from said stop prior to the initial feeding movement of the shelf.
5. A feeder for rotary printing machines embodying therein a fixed support adjacent the printing line of the printing couple adapted to receive a portion of the sheet to be fed, adjacent its forward edge, a front gauge stop movable towards and from said support, actuating means for said stop whereby it will be alternately interposed in the path of the sheet so as to engage its forward edge and position it with relation to the printing couple for longitudinal register, and moved away from said support to permit the sheet to be fed, a reciprocatory feed shelf, a rock shaft carried by said shelf, gripper fingers carried by said shaft, including therein a flat spring portion adapted to engage the sheet and flex under engagement therewith, a spring acting thereon and having a normal tendency to rotate said shaft so as to engage the gripper fingers with the feed shelf, a crank arm carried by said shaft, a fixed cam adapted to engage said crank arm toward the limit of the feeding movement of the feed shelf, a stop upon said shaft, a holding dog having a normal tendency to engage said stop, actuating means adapted to impart reciprocatory movement to the feed shelf, and a trip mechanism operative upon said holding dog actuated in synchronism with said last named actuating means, whereby said latch member will be disengaged from said stop prior to the initial feeding movement of the shelf.
6. A feeder for rotary printing machines embodying therein a fixed support adjacent the printing line of the printing couple adapted to receive a portion of the sheet to be fed, adjacent its forward edge, a front gauge stop movable towards and from said support, actuating means for said stop whereby it will be alternately interposed in the path of the sheet so as to engage its forward edge and position it with relation to the printing couple for longitudinal register, and moved away from said support to permit the sheet to be fed, a reciprocatory feed shelf, a rock shaft carried by said shelf, gripper fingers carried by said shaft, a spring acting thereon and having a normal tendency to rotate said shaft so as to engage the gripper fingers with the feed shelf, a crank arm carried by said shaft, a fixed cam adapted to engage said crank arm toward the

limit of the feeding movement of the feed shelf, a stop upon said shaft, a holding dog having a normal tendency to engage said stop, actuating means adapted to impart 6 reciprocal movement to the feed shelf, a push rod adapted to engage said holding dog, and actuating means for said push rod whereby said dog will be disengaged from its 10 co-operating stop prior to the initial feeding movement of the shelf.

7. A feeder for rotary printing machines embodying therein a fixed support adjacent the printing line of the printing couple adapted to receive a portion of the sheet to 15 be fed, adjacent its forward edge, a front gauge stop movable towards and from said support, a rock shaft carrying said front gauge stop, means having a normal tendency to raise said stop from said support, a crank 20 arm operative upon said rock shaft, a cam carried by one of the members of the printing couple adapted to engage said front gauge with said support after the feeding of each sheet to said printing couple, and 25 permit the disengagement of the gauge from said support prior to the next feeding operation, and means adapted to impart feeding movement to a sheet across said support.

8. A feeder for rotary printing machines 30 embodying therein a fixed support adjacent the printing line of the printing couple adapted to receive a portion of the sheet to be fed, adjacent its forward edge, a front gauge stop movable towards and from said support 35 consisting of metal having converging arms provided with downturned forked ends, lugs upon said support adapted to receive the forked ends of said arms, a rock shaft carrying said front gauge stop, means having 40 a normal tendency to raise said stop from said support, a crank arm operative upon said rock shaft, a cam carried by one of the members of the printing couple adapted to engage said front gauge with said support 45 after the feeding of each sheet to said printing couple, and permit the disengagement of the gauge from said support prior to the next feeding operation, and means adapted to impart feeding movement to a sheet across said support.

9. A feeder for rotary printing machines embodying therein a fixed support adjacent the printing line of the printing couple adapted to receive a portion of the sheet to 55 be fed, adjacent its forward edge, a front gauge stop movable towards and from said support consisting of metal having converging arms provided with downturned forked ends, lugs upon said support 60 adapted to receive the forked ends of said arms, means whereby said support and said arms may be adjusted laterally of the machine, a rock shaft carrying said front gauge stop, means having a normal 65 tendency to raise said stop from said sup-

port, a crank arm operative upon said rock shaft, a cam carried by one of the members of the printing couple adapted to engage said front gauge with said support after the feeding of each sheet to said printing couple, 70 and permit the disengagement of the gauge from said support prior to the next feeding operation, and means adapted to impart feeding movement to a sheet across said support. 75

10. A feeder for rotary printing machines embodying therein a fixed support adjacent the printing line of the printing couple adapted to receive a portion of the sheet to be fed, adjacent its forward edge, a front 80 gauge stop movable towards and from said support, a rock shaft carrying said front gauge stop, means having a normal tendency to raise said stop from said support, a crank arm operative upon said rock shaft, a cam carried by one of the members of the printing couple adapted to engage said front gauge with said support after the feeding of each sheet to said printing couple, and permit the disengagement of the gauge from 85 said support prior to the next feeding operation, means whereby said cam may be adjusted circumferentially of the printing couple member to secure accuracy in the timing of the actuation of said front gauge, and means adapted to impart feeding movement to a sheet across said support. 90

11. A feeder for rotary printing machines embodying therein a fixed support adjacent the printing line of the printing couple adapted to receive a portion of the sheet to be fed, adjacent its forward edge, a front gauge stop movable towards and from said support, a rock shaft carrying said front gauge stop, means having a normal tendency to raise said stop from said support, a crank arm operative upon said rock shaft, a segment fixed in relation to one of the members of said printing couple, a slide mounted upon said segment, means whereby said slide may be adjusted with relation to said segment, a cam carried by said slide adapted to engage said front gauge with said support after the feeding of each sheet to said printing couple, and permit the disengagement of the gauge from said support prior to the next feeding operation, and means adapted to impart feeding movement to a sheet across said support. 110

12. A feeder for rotary printing machines embodying therein a fixed support adjacent the printing line of the printing couple adapted to receive a portion of the sheet to be fed, adjacent its forward edge, a front gauge stop movable towards and from said support, actuating means for said stop whereby it will be alternately interposed in the path of the sheet so as to engage its forward edge and position it with relation to the printing couple for longitudinal regis- 125

- ter, and moved away from said support to permit the sheet to be fed, a reciprocatory feed shelf, a double crank shaft, a pitman connecting one of the cranks of said shaft 5 with said shelf, an oscillatory shaft, connections between said shaft and the other crank of said crank shaft, a cam carried by one of the members of said printing couple and operative upon said rock arm, whereby said feed shelf will receive a timely reciprocation, grippers carried thereby, means adapted to cause engagement of said grippers with a sheet prior to a feeding movement of said shelf whereby a sheet will be fed across said support, and means adapted to disengage said grippers from the sheet substantially simultaneously with the engagement of the forward edge of the sheet by the members of the printing couple. 10 13. A feeder for rotary printing machines embodying therein a fixed support adjacent the printing line of the printing couple adapted to receive a portion of the sheet to be fed, adjacent its forward edge, 15 a front gauge stop movable towards and from said support, actuating means for said stop whereby it will be alternately interposed in the path of the sheet so as to engage its forward edge and position it with relation to the printing couple for longitudinal register, and moved away from said support to permit the sheet to be fed, a reciprocatory feed shelf, grippers carried thereby, means adapted to cause engagement 20 of said grippers with a sheet prior to a feeding movement of said shelf whereby a sheet will be fed across said support, means adapted to disengage said grippers from the sheet substantially simultaneously with the engagement of the forward edge of the sheet by the members of the printing couple, and a fixed feed shelf adapted to contain a stack of sheets adjacent said reciprocatory feed shelf. 25 14. A feeder for rotary printing machines embodying therein a fixed support adjacent the printing line of the printing couple adapted to receive a portion of the sheet to be fed, adjacent its forward edge, a front gauge stop movable towards and from said support, actuating means for said stop whereby it will be alternately interposed in the path of the sheet so as to engage its forward edge and position it with relation to the printing couple for longitudinal register, and moved away from said support to permit the sheet to be fed, a reciprocatory feed shelf, a rock shaft carried by said shelf, gripper fingers carried by said shaft, a spring acting thereon and having a normal tendency to rotate said shaft so as to engage the gripper fingers 30 with the feed shelf, a crank arm carried by said shaft, a fixed cam adapted to engage said crank arm toward the limit of the feeding movement of the feed shelf, a stop upon said shaft, a holding dog having a normal tendency to engage said stop, actuating means adapted to impart reciprocatory movement to the feed shelf, a push rod adapted to engage said holding dog, a rock arm pivotally connected with said push rod, 35 a rotatable cam adapted to operatively engage said rock arm, a spring operative upon said rock arm in opposition to said cam, and means rotating said cam in synchronism with the printing couple, whereby said rock arm will be actuated prior to each feeding movement of the feed shelf. 40 In witness whereof I have hereunto affixed my signature this 1st day of February, 1922.

FRANK C. MARQUARDT.
